UNITED STATES PATENT OFFICE.

JAMES M. ROBERTS, OF ANDREW COUNTY, NEAR ST. JOSEPH, MISSOURI.

WIRE STRETCHER AND SPLICER COMBINED.

1,384,853.

Specification of Letters Patent. Patented July 19, 1921.

Application filed March 16, 1920. Serial No. 366,208.

To all whom it may concern:

Be it known that I, JAMES M. ROBERTS, a citizen of the United States, residing in Andrew county, near St. Joseph, in the county of Buchanan and State of Missouri, have invented certain new and useful Improvements in Wire Stretchers and Splicers Combined, of which the following is a specification, reference being had therein to the accompanying drawings.

My invention relates to improvements in wire stretchers and splicers, combined; and the objects of my improvements are, first; to provide a simple, substantial and durable mechanism of this class, which shall be thoroughly efficient and be cheap in cost of manufacture, second; to so construct and arrange the parts of said mechanism, that a broken wire, either smooth or barbed, can be stretched and be held taut at any point while said wire is being spliced, and will leave the wire tightly stretched after said splice is made, third; to provide ready means whereby the mechanism can be easily and quickly attached to and detached from the wire being served thereby, fourth; to provide wire holding means whereby two ends of any wire, whether loose or stretched are held for splicing the same, which splicing can be done with the hands or with a pair of pliers.

I attain these objects by the mechanism illustrated in the accompanying drawings, in which:

Figure 1 is a front view of the wire stretcher and splicer, combined, showing the parts in position for stretching a wire. Fig. 2 is a transverse section on the line 1 1, seen in Fig. 1, looking toward the left. Fig. 3 is an end view in detail of the rack guide and of one of the suspending hooks, looking toward the left. Fig. 4 is a section similar to Fig. 2, showing the vise in detail, holding the end portions of a wire to be spliced.

Referring to Fig. 1 the rack 3 is slidably mounted in the rack guide 2. Said rack is moved longitudinally, either toward the right or left, in said guide, by rotation of the worm wheel 4, the worm threads of which are in engagement with the teeth of said rack. Said worm wheel is secured on the shaft 5, which is rotatably mounted in the lower ends of the standards 6, the upper ends of which are formed integrally with said rack guide.

The crank 7 is secured on one end of said

shaft, whereby said shaft and the thereon secured worm wheel are manually rotated.

The eccentrically mounted wire clamp 8 is provided with the handle 9, by which said clamp is oscillated on its pivot 10; which pivot is secured in the upper end portion of the standard 11.

The lower end of the standard is rigidly connected with the central portion of the top of the rack 3, above which said standard projects through a slot formed longitudinally through the top of the rack guide 2, throughout its entire length.

The clamp seat 11' (see Fig. 2,) is formed on one side of said standard, on which seat the end portion of the splice wire 12 is clamped by the clamp 8.

It will be seen in Fig. 1, that said clamp has fine ratchet teeth formed on its face, which teeth are so inclined that the stretching of the splice wire 12, oscillates the clamp 8 clockwise, thereby tightening said clamp upon said splice wire.

The fixed clamp 13 is provided with the handle 14, and is oscillatably mounted on the upper end portion of the standard 15, the lower end portion of which is formed integrally with the rack guide 2. The clamp 13 is the same in construction and operation as the previously described clamp 8, except that it is reversed in position, for holding the end portion 16 of the wire, against stress in the opposite direction.

The described rack guide and its connected parts are supported in position for operation, by grasping the grip flanges 17, which are formed on the outer portion of each one of the standards 6, until by rotation of the crank 7, the therewith connected parts have drawn tight the end portions 12 and 16 of the wire. After this the mechanism is suspended from said portions of wire by the hooks 18 and 19, which are respectively hooked thereon.

Said hooks are the same in construction and operation, as seen in Fig. 3, except that the hook 18 is detachably secured on one end of the rack guide 3, by the set screw 18', while the hook 19 is secured on the opposite end of said guide by welding or brazing.

The brackets 20 are formed with said rack guide on the front thereof.

One end of each one of the links 21 is oscillatably connected with said brackets respectively. The ends of the bifurcations of the bifurcated vise body 22 are respectively

connected with the free ends of said links, by the pivot bolt 23, for oscillation thereon. The movable jaw 24 is mounted between the bifurcations of the vise body 22, for slideable movement thereon. The fixed jaw 25 is formed integrally with the free ends of said bifurcations. The cam 26 is oscillatably mounted between the ends of said bifurcations, on the central portion of the pivot bolt 23, with the face of the cam against the adjacent surface of the vise jaw 24. Said cam is provided with the handle 27, formed integrally therewith.

10 The described vise is used for holding one end of the wire 12' and of the wire splice piece 12, clamped between the jaws 24 and 25, while making the splice 28, which splice is seen in Fig. 1.

15 In operation, with the parts in the position seen in Fig. 1, the operator of the described wire stretcher and splicer, with one hand grasps the grip flanges 17, which are at the left of the worm wheel 4, and with the other hand rotates the crank 7, which, by the previously described worm and rack movement carries the clamp standard 11 and the therewith connected clamp 8, from the position shown, to the center of the mechanism. This movement of the clamp stretches the 20 unshown slack in the wire 12', after which, continued rotation of said crank, worms the rack guide 2 and the thereby carried parts toward the left, until the clamp 8 is over the right end portion of the mechanism, as indicated by dotted lines.

25 While the parts of the mechanism are in this position, with all of the wires 12', 12 and 16 tightly stretched, the operator removes his hands from said grip flanges and 30 crank, leaving the machine suspended on said tightened wire, by the suspending hooks 18 and 19. He then moves the previously described vise from the position shown in Figs. 2 and 1, to the position shown in Fig. 4, in which position the cam handle 27 is thereby moved to a vertical position.

35 The operator then forces the cam handle 27 from its described vertical position to the position seen in Fig. 4, thereby moving the jaw 24 toward the jaw 25, tightly clamping said wire portions between said jaws. He then removes the clamped portions of said wire from the clamps 8 and 13, and there- 40 after removes the wire 12' and the end portion 16 of the wire, from the hooks 18 and 19 respectively, after which the parts of the mechanism gravitate from the position seen in Fig. 2, to the position seen in Fig. 4, for providing space between said wire portions 45 and the rack guide 2, in which to perform the following described operations.

50 Said operator twists the free end of the splice wire 12 and of the end portion 16 of the wire, around the adjacent portions of 55 the stretched wire, forming another splice,

which is the same in construction and operation as the splice 28. He then moves the cam handle 27 from the position shown in Fig. 4, to a vertical position, thereby loosening the vise jaws 24 and 25 from said wire 70 portions and removes the described vise therefrom, leaving the thus spliced wire tightly stretched.

75 The described twisting of the wire ends, may be done with the hands of the operator, or by the use of a pair of pliers not shown.

80 Said operator then carries the described mechanism to another broken wire, onto which he splices another splice piece of wire, as previously described, after which he places the wire portions in the clamps 8 and 13, and in the hooks 18 and 19, as shown in Fig. 1, after which the previously described operations are repeated.

85 Having fully described my invention, what I claim as new and desire to secure by Letters Patent, is:

1. A rack guide having a slot formed through its top throughout the entire length thereof and an opening formed through the central portion of its bottom; a clamp standard the lower end portion of which is formed integrally with the central portion of one side of said rack guide; a clamp seat formed on one side of said standard; a clamp member oscillatably mounted on the same side of said standard for clamping a wire between said seat and said member by oscillation of the latter; a rack mounted for slideable movement in said rack guide; a movable clamp standard the lower end of which is secured on the upper surface of said rack and extends thereabove through said rack guide slot, said movable standard being provided with a clamp seat and clamp member 105 similar to the first mentioned clamp standard; a pair of standards the upper ends of which are formed integrally with said rack guide; a shaft the ends of which are rotatably mounted in the lower ends of said 110 standards; a worm wheel secured on the central portion of said shaft the worm threads of which project from said wheel through the bottom opening through the bottom of said rack guide into engagement with the 115 teeth of said rack; a crank secured on one of the extremities of said shaft; and a suspending hook connected with each end of said rack guide whereby the hereinbefore claimed parts are suspended from a stretched 120 wire.

125 2. In a wire stretcher and splicer, combined; a rack guide; a fixed wire clamp rigidly connected with said rack guide for detachably holding an end portion of a wire therein; a rack mounted for slideable movement in said guide; sliding means whereby said rack is slid longitudinally in said guide; a movable wire clamp securely connected with the central portion of said rack for 130

clamping the opposite end portion of a wire
therein; rack sliding means whereby said
rack is longitudinally slid thereby moving
said movable clamp and the therein clamped
portion of a wire toward and past the first
5 mentioned wire clamp for tightly stretching
said wire; a vise wherein the portions of
said wire which are stretched between said
wire clamps are tightly clamped for holding
10 said parts of wire against longitudinal move-
ment; vise suspending means between the
free ends of which said vise is oscillatably
suspended; and supporting means whereby
the other ends of said suspending means are
15 oscillatably connected with one side of said
rack guide.

3. In a wire stretcher and splicer, com-
bined; a rack guide; a rack mounted for
20 slideable movement in said rack guide; wire
holding means for detachably and separately
holding the two ends of a broken wire; mov-
ing means whereby said wire holding means
are moved toward and past each other there-

by stretching said broken wire; a pair of
brackets connected with one side of said rack
25 guide at a point which is between and to one
side of the thus moved wire holding means;
a link for each one of said brackets one end
of each one of said links being oscillatably
connected with its respective bracket; a
30 pivot bolt through the other ends of said
links; a bifurcated vise body; a vise jaw
formed integrally with the free ends of the
bifurcations of said body, the other ends of
said bifurcations being oscillatably mounted
35 on said pivot bolt; a jaw mounted on said
bifurcations for slideable movement therebe-
tween; and a cam provided with a handle
therefor, said cam being oscillatably mount-
ed on the central portion of said pivot bolt
40 between the pivoted ends of said bifurca-
tions with its face against the adjacent sur-
face of said slideably mounted jaw.

In testimony whereof I affix my signature.

JAMES M. ROBERTS.
